UNITED STATES PATENT OFFICE.

JOSEPH E. KENNEDY, OF NEW YORK, N. Y.

PLANT FOR FEEDING PULVERIZED COAL TO FURNACES.

1,320,367.

Specification of Letters Patent.

Patented Oct. 28, 1919.

Application filed March 18, 1918. Serial No. 223,021.

To all whom it may concern:

Be it known that I, JOSEPH E. KENNEDY, a citizen of the United States, and a resident of the borough of Manhattan, city, county, and State of New York, have invented certain new and useful Improvements in Plants for Feeding Pulverized Coal to Furnaces, of which the following is a specification.

While applicable to the feeding of pulverized coal to furnaces generally, my coal reducing and feeding plant is designed more particularly for use on marine vessels, the main object being the provision of a self-contained system whereby the raw coal is manipulated continuously from and including the crusher to the combustion chamber of the furnaces, as hereinafter more fully set forth, described, and claimed specifically, a distinctive feature being the utilization of the waste products of combustion from the boiler to effect the elimination of moisture from the crushed coal prior to its introduction into the pulverizer. By waste products of combustion I herein mean those that have already performed the function of heating the water in the boiler, and that would otherwise be discharged with loss of heat which it is my purpose to save and utilize as a means of drying the fuel preparatory to its introduction in pulverized state into the furnace of the boiler from which such waste products are derived.

In the accompanying drawings,

Figure 1, represents diagrammatically a plan of a coal reducing and feeding plant embodying the essential features of my invention;

Fig. 2, represents a front view thereof;

Fig. 3, is an elevation of the left hand side of the plant;

Fig. 4, is an elevation of the right hand side thereof.

B, B, represents twin boilers of the "Scotch" marine type, the waste products of combustion from which, after heating the water in the boilers, pass into the flues b, b, communicating with the exhaust stack b'.

The preliminary reduction of the coal is effected in a crusher C, of the usual type (actuated by the motor C') which crusher C, delivers the coal through the chute c, to the bottom of the elevator E, which latter is of the chain bucket or any other suitable type. The elevating mechanism (actuated by the motor E') transfers the broken coal

through the chute e, to the upper end of the gravity drop drier D, through which it descends in a tortuous course to the conduit d, which delivers it to a pulverizer P, preferably of the type set forth in my concurrent application Serial No. 215,052, filed Feb. 2, 1918. The reduction mechanism within the pulverizer P, is actuated by the motor P', through the medium of the power shaft p', in the usual manner.

In its descent through the drier D, the coal passes through an upward current of the hot otherwise waste gaseous products of combustion derived from the boilers, and diverted into the drier D, from the bottom of the stack b', through the lateral flue b², to return to the stack b', from the upper part of the drier D, through the flue b³. Suitable dampers b⁴, b⁵, b⁶, in the stack b', and branch flues b², b³, control and regulate the flow of these waste gaseous products of combustion through the drier D, said products passing off finally through the stack b', and taking with them the moisture extracted from the broken coal in the drier D.

Thus by closing the damper b⁴, more or less in the lower part of the main stack b', and opening the dampers b⁵, and b⁶, in the lateral flues b², b³, more or less, more or less of the heated gaseous products of combustion may be diverted through the drier D, as may be found most expedient; and to facilitate this action a forced draft may be induced by a blower F, driven by a motor F', arranged to inject air upward under pressure into the main stack b', above the upper lateral flue b³, in a manner well known in the art.

As set forth in my concurrent application heretofore referred to a forced circulation of air under pressure is maintained through the pulverizer P, and collectors Q, Q', and conduits p, p', p², by any suitable means, as by the exhaust fan F², and motor F³. The comminuted coal collected in the cyclones Q, Q', is delivered through conduits q, q', to the feed trough T, the screw conveyer t, of which is actuated by the motor T', and gears t², t³.

The feed trough T, is positioned over the series of hoppers H, and provided with a series of gates t⁴, t⁴, coincident therewith and for the control of the feed of pulverized coal to said hoppers H, H, individually and collectively. The lower portion of each hop-

per H, H, communicates with a coal spout h, in which is interposed the usual gate h'. The spout h, supplies the comminuted coal to the nozzle h², in the burner b², communicating with one of the combustion chambers in one of the marine boilers B, air under pressure being supplied to said burner b², in the usual manner by means of a branch pipe r, connected with the pressure main R, and 10 provided with a regulating valve r'.

By my construction and arrangement of parts "miners run" of coarse coal may be taken directly from the ships' bunkers and by a continuous, substantially automatic 15 process, reduced, dried, comminuted and fed as required to the furnace or furnaces, the whole plant being compact and complete in this respect and in every particular.

While adaptable for use for various other 20 purposes, my plant is especially efficacious for stoking marine boilers, since the vessel provided therewith will not be dependent upon pulverized coal supply stations at its various ports of entry, but can ship the coal 25 in the rough state, and comminute it as required for immediate use, thus overcoming the main difficulty heretofore experienced in the employment of pulverized coal as a fuel for marine boilers.

Furthermore the coal thus freshly crushed 30 dried, and pulverized, and introduced directly into the furnace has no chance to deteriorate by reason of storage, and is in the best possible condition for economical and 35 perfect combustion in the furnace; and the utilization of the otherwise waste gaseous products of combustion (derived directly from the boiler of the furnace to be fed) for the purpose of drying the crushed coal 40 immediately prior to its further reduction in the pulverizing apparatus is an important factor in rendering the plant effective. In fact this utilization of these waste gaseous products of combustion is the essential feature 45 which enables me to attain, in a relatively small and compact area, a continuous system and process for the reduction of the bunker coal to a pulverized fuel for practically immediate injection into the furnace 50 or furnaces as set forth; and the heat thus conserved represents a material saving in the cost of production of such comminuted fuel.

It will be seen from the foregoing description 55 that "miners run" bunker coal, fed to the crushing apparatus C, is delivered by the latter through the chute e, to the bottom of the elevator E, by which latter it is transferred through the chute e, to the top of 60 the drier D, through which it discards waste products of combustion derived from the boiler B, to the pulverizer P, through the conduit d, the pulverized material being carried by air pressure to the collectors Q, Q', by which it is delivered to 65

the feed trough T, which delivers the fuel thus prepared to the hoppers H, H, which in turn deliver it through the spouts h, to air blast nozzles h², by which it is injected into the furnaces. Thus, by a continuous 70 process and sequence of connected operations, rough "bunker" coal, by the utilization of the heat of waste gaseous products of combustion derived from the boiler or 75 boilers, is rendered fit for introduction and consumption in the furnace or furnaces of the very boiler or boilers from which such otherwise waste products of combustion are withdrawn.

What I claim as my invention and desire 80 to secure by Letters Patent is,

1. A fuel feed plant of the character designated, comprising a boiler and furnace, means for crushing raw coal and transferring it to a gravity drop drier, said gravity 85 drop drier and means for diverting the waste gaseous products of combustion from said boiler therethrough, means for delivering the coal from the drier to pulverizing means, said pulverizing means and means 90 for injecting the dried and pulverized coal under air blast into the furnace of the boiler from which the waste products of combustion were derived to dry the fuel as and for the purpose set forth. 95

2. A fuel feed plant of the character designated, comprising a boiler and furnace, means for crushing raw coal and transferring it to a gravity drop drier, said gravity drop drier and means for diverting the 100 waste gaseous products of combustion from said boiler therethrough, means for delivering the coal from the drier to pulverizing means, said pulverizing means, means for delivering the dried and pulverized coal to 105 a hopper, said hopper and air blast means for injecting the pulverized coal therefrom into the furnace of the boiler from which the waste products of combustion were derived to dry the fuel, as and for the purpose 110 set forth.

3. A fuel feed plant of the character designated, comprising a plurality of boilers and furnaces, means for crushing raw coal and transferring it to a gravity drop drier, 115 said gravity drop drier and means for diverting the waste gaseous product of combustion from said boilers therethrough, means for delivering the coal from the drier to pulverizing means, said pulverizing means and means for delivering the pulverized coal to a conveyer, a plurality of hoppers communicating with said conveyer, and air blast means for injecting the pulverized coal from 120 said hoppers into the furnaces of the boilers 125 from which the waste products of combustion were derived to dry the fuel, as and for the purpose set forth.

4. A fuel feed plant of the character designated, comprising a plurality of boilers 130

- and furnaces, means for crushing raw coal and transferring it to a gravity drop drier, said gravity drop drier and means for diverting the waste gaseous product of combustion from said boiler therethrough, means for creating a forced draft of, and for regulating the flow of, said waste gaseous products of combustion through said gravity drop drier, means for delivering the coal from the drier to a conveyer, a plurality of hoppers 5 communicating with said conveyer, and air blast means for injecting the pulverized coal from said hoppers into the furnaces of the boilers from which the waste products of combustion were derived to dry the fuel, together with means for controlling the flow of dried and pulverized coal into said hoppers and from said hoppers into the furnaces, as and for the purpose set forth.
5. A fuel feed plant of the character designated, comprising a boiler and furnace, means for crushing raw coal and transferring it to a gravity drop drier, said gravity drop drier and means for diverting the waste gaseous products of combustion from said boiler therethrough, means for creating a forced draft of said waste gaseous products of combustion through said gravity drop drier, means for delivering the coal from the drier to pulverizing means, said pulverizing 20 means and means for injecting the dried and pulverized coal under air blast into the furnace of the boiler from which the waste products of combustion were derived to dry the fuel as and for the purpose set forth.
6. A fuel feed plant of the character designated, comprising a boiler and furnace, means for crushing raw coal and transfer-
- ring it to a gravity drop drier, said gravity drop drier and means for diverting the waste gaseous products of combustion from said boiler therethrough, means for creating a forced draft of, and for regulating the flow of, said waste gaseous products of combustion through said gravity drop drier, means for delivering the coal from the drier to pulverizing means, said pulverizing means and means for injecting the direct and pulverized coal under air blast into the furnace of the boiler from which the waste products of combustion were derived to dry the fuel as and for the purpose set forth.
7. In a fuel feed plant of the character designated, means for drawing the hot gases from the combustion chamber through a shunt pipe, passing them through a tower drier, and returning them to their source, together with means for passing coal through said tower drier to the pulverizing mechanism.
8. The method herein described of preparing and feeding pulverized coal to a boiler furnace, consisting in subjecting the crushed coal to a current of waste gaseous products of combustion derived from the boiler to eliminate the moisture from said crushed coal, pulverizing the coal thus dried, and injecting it by means of air blast into the furnace of the boiler from which said waste products of combustion were derived, substantially as set forth.
